United States Patent Office.

C. J. O'HARA, OF NEW ORLEANS, LOUISIANA.

Letters Patent No. 82,544, dated September 29, 1868.

IMPROVEMENT IN NAME-PLATES FOR STREET-LAMPS.

The Schedule referred to in these Letters Patent and making part of the same.

TO ALL WHOM IT MAY CONCERN:

Be it known that I, C. J. O'HARA, of the city of New Orleans, parish of Orleans, and State of Louisiana, have invented a certain new, useful, and improved Mode of Placing the Names of Streets on Street-Lamps; and I do hereby declare the following to be a full, clear, and exact description of the same, reference being had to the annexed drawing, making a part of this specification, in which—

Figure 1 is a front view of one side of a street-lamp with my improvement attached thereto, and

Figure 2 a sectional edge view in the line $a b$ of one side of a street-lamp, with my improvement attached.

My invention has for its object to provide a cheap and expeditious means of placing the names of streets on street-lamps, without painting the same upon the glass sides of the lamps, or taking down the lamp, or in any other manner interfering with the same, and so, also, as that the glass sides of the lamps may be kept clean, and the name of the street be preserved intact, even although said sides be broken or entirely withdrawn; and my invention consists of a narrow piece of glass or other equivalent substance, on which the name of the street is painted, that is enclosed in and protected by a metallic-edge frame, having inclined or bevelled ends, in order that said ends may conform to the inclination of the corner-pieces of the lamp to which it is applied, which is placed inside the lamp, and sustained near the glass, on the side of the lamp on which the name of the street is to show, by the two opposing ledges or flanches upon the corner-pieces of the lamp-frame, against which the contiguous ends of the two flanking panes of glass are supported, and secured from falling out by broad oblate or flat hooks, the ends of which clasp the flanches of the same corner-pieces of the lamp that support the pane of glass that is immediately in front of it.

But my invention will be better and more quickly understood by referring to the drawing.

A A' are two corner-pieces of an ordinary street-lamp, which, it will be observed, consists of a circular bar, usually hollow, from which, at right angles to each other, project two flanches, $a a'$, for the support of the glass sides of the lamp. B is a pane of glass covering the side of a lamp, as when it is made in the usual manner, and C the piece of glass on which the name of a street is written. This piece of glass is protected upon its edges by a metallic frame, b , to the ends of which are attached the hooks $c c'$, which take over the flanches $a a'$, that project from the corner-pieces A A', and so constitute grooves in which the said flanches fit.

The lamp or lamp-frame being wider at top than at bottom, the supplemental piece C, which I may very properly call the "name-plate," can be placed in its position or place without the slightest difficulty, and whenever the lamp needs to be cleaned, it can be withdrawn as readily as it was put into place, by simply lifting it up until it attains to a point at which the width of the lamp, or the space between the corner-pieces thereof, becomes greater than its own length. When in its place, the hooks $c c'$, in connection with the inclined form of its ends, and the corresponding inclination of the corner-pieces of the lamp-frame, hold it so securely that it cannot be displaced by any accident to which street-lamps are liable, even although it be broken by the violence thereof, as well as the glass sides of the lamp. For, even if broken, the edge-frame b will prevent it from falling out, whilst the breaking of the glass constituting the sides or walls of the lamp, does not affect it in the slightest degree. Hence it will be seen, that under all circumstances and conditions, the great object intended to be secured by my invention, to wit, the indication of the name of the street on the street-lamps is attained with absolute certainty. It will be observed, furthermore, that by means of my invention the names of the streets lighted by them may be put on every street-lamp with very little expense, because the plates C may be framed, and have the proper names put or painted on them at one shop or place for each city or town, as the case may be, and then carried in a wagon, and, without the use of a ladder, from the wagon itself be quickly put into each lamp. The name-plate may be inserted or fixed, in relation to the top and bottom of the lamp, about as shown on the drawing; or it may be placed higher up or lower down, but in no case should it be put low enough down to throw a shadow on the pavements lighted by the lamp to which it is applied.

Having thus described my invention, what I claim, and desire to secure by Letters Patent, is—

The mode herein described of marking or placing the names of streets upon street-lamps, by means of a transverse supplemental "name-plate," C, when the same is provided with an edge-frame, b , bevelled ends, and oblate hooks $c c'$, and is applied or placed within the lamp, as herein described for the purpose set forth.

C. J. O'HARA.
